S. W. CARPENTER.

Cleaning Gas Retorts.

No. 18,791.

Patented Dec. 1, 1857.

UNITED STATES PATENT OFFICE.

SIMMONS W. CARPENTER, OF YONKERS, NEW YORK, ASSIGNOR TO WILLIAM W. WOODWORTH, OF SAME PLACE.

CLEANSING GAS-RETORTS.

Specification of Letters Patent No. 18,791, dated December 1, 1857.

To all whom it may concern:

Be it known that I, SIMMONS W. CARPENTER, of the town of Yonkers, in the county of Westchester and State of New York, have 5 invented a new and useful Improvement in the Method of Cleansing the Retorts of Portable Gas Apparatus and the Siphons and Pipes Connected Therewith; and I do hereby declare that the following is a full 10 and exact description thereof, reference being had to the accompanying drawings and to the letters of reference marked thereon.

The drawings represent a portable gas apparatus substantially as the same is now 15 manufactured and erected by C. R. Woodworth & Co., of New York city, a portion of the apparatus being represented in transverse section.

The nature of my invention consists in re- 20 moving the carbonaceous matter remaining in the retorts of gas apparatus after the charge is exhausted, also in cleansing the pipes, tubes, and siphons connected with the apparatus of and from any and all foreign 25 deposits formed therein from the tarry and ammoniacal or other vapors or liquor created in the process of manufacturing gas, by the use of steam or steam generated and applied as follows:

30 The charge in the retort A having become exhausted, and the said retort together with the pipes B, C, and D, needing to be cleansed, I first heat the retort until the same is of a bright cherry red, I then turn the stop cock 35 E so as to shut off the connection through the same with the gasometer O, I then introduce water slowly into the retort A, through the siphon pipe S. The water on reaching the heated retort is instantly con- 40 verted into steam or stam and by the force

of its own pressure rushes with great velocity and effect through the pipes B, C, and D, into the siphon box, and escapes through the siphon P. Thus almost instantaneously, thoroughly cleansing every part of the gas 45 apparatus subject to deposits or at all liable to become foul.

I am aware that steam is employed in the manufacturing of gas for the purpose of keeping the retorts and pipes free from carbonaceous deposits, as for example in the apparatus patented and used by N. Aubin, but in such cases the use of the steam is coincident with the generation of the gas, and the whole apparatus is thereby rendered more 55 complicated and expensive, and at the same time, when used in such manner, is of doubtful utility. On the contrary the method invented by me and described above while it is thorough and efficient in effect, it is also 60 exceedingly simple, and almost wholly inexpensive.

I do not claim as my invention the principle of the use of steam or stam as a 65 cleanser of gas apparatus, but

What I do claim as my invention and desire to secure by Letters Patent is—

The method or process of the introduction of water directly into the heated retort (the charge being drawn or exhausted) there to 70 be converted into steam or stam, free to unite with and remove the carbonaceous or other deposit contained in the retort or pipes, substantially in the manner herein set forth.

SIMMONS W. CARPENTER.
